UNITED STATES PATENT OFFICE.

FRANK MICHAEL CRYSTLER, OF BELDING, MICHIGAN.

SIGNAL.

Application filed August 11, 1924. Serial No. 731,464.

This invention relates to signals for automobiles and has for its object the provision of a toy in the shape of a figure having a removable cap in which is adapted to be 5 removably mounted a light bulb, said light bulb being connected with a source of electric current, and a switch in the circuit which is manually operated either through a push button or through some movable 10 element which controls the operation of the machine and which contact, when operated, causes closing or opening of the circuit.

This invention will be best understood from a consideration of the following detailed description, in view of the accompanying drawing forming a part of the specification; nevertheless it is to be understood that the invention is not confined to the disclosure, being susceptible of such changes 20 and modifications, which shall define no material departure from the salient features of the invention as expressed in the appended claims.

In the drawings:

25 Figure 1 is a side view of an automobile showing my invention applied thereto.

Figure 2 is a vertical section in elevation of the signal taken along the line 2—2 of Figure 7.

30 Figure 3 is a view in perspective of a member providing a contact and at the same time providing means for enclosing the wires of a portion of the circuit.

Figure 4 is a horizontal section of the 35 figure taken along the line 4—4 of Figure 2.

Figure 5 is a view in perspective of a contact member adapted to be supported in the hat of the figure.

Figure 6 is a view in perspective of the 40 elements composing the circuit and the various contacts which are enclosed within the figure and shown in detached relation.

Figure 7 is a horizontal section of the head and hat of the figure.

45 Figure 8 is a horizontal section taken along the line 8—8 of Figure 2.

Figure 9 is a fragmentary vertical section taken along the line 9—9 of Figure 7.

Figure 10 is a fragmentary vertical section 50 taken along the line 10—10 of Figure 7.

Referring more particularly to the drawings, 1 designates a toy in the form of the well known kewpie doll and is made of some transparent material such as celluloid 55 adapted to be secured by means of a cup-shaped base plate 2 to the radiator cap 3 of

the automobile 4. The figure may be of any well known shape other than a kewpie doll and is connected to the radiator cap by the cup-shaped member 2 through screws 60 5 which pass through perforations in flanges 5^a in the cup-shaped member 2, and a non-metallic insulating disc 6 secured to the metal member 2.

A channel member 7 is provided with an 65 integrally formed metal foot 11 having perforations in which are inserted insulating sleeves 12. The channel member 9 has an integrally formed foot 13 and the perforations in the foot are provided with insulating sleeves 14. The passages in the sleeves 12 are adapted to align with passages 15 in the insulating disc 6 and with passages in the insulating sleeves 16 mounted in perforations in the top 17 of the base member 2. 75 Passages in the insulating sleeves 14 of the foot 13 align with passages 18 in the insulating disc or plate 6 and also with the passages 19 in the top 17 of the base member 2. Mounted upon the feet 11 and 13 of the 80 respective standards 7 and 9 is an insulating plate 20 while a metal conductor 21 is mounted upon the top of the insulating member 20. Screws 22 and 23 are insulated through perforations in the conductor 21, 85 insulating member 20, the foot 11, insulating disc 6 and are screwed into the threaded passages in the sleeves 16 mounted in the perforations in the top 17 of the base member 2. 90

It will be seen that the sleeves 16 are provided with flanges 24 at their lower ends in order to maintain the sleeve 16 within the passage. Screws 25 and 26 pass through the passages in the sleeve 14, the perforations 18 and the disc 6 and have their lower ends screwed into the threaded passages 19 in the top 17 of the base member 2. The screws 25 and 26 also pass through the perforations in the conductor 21 and the 100 insulating member 20.

An insulated electrical wire 27 passes through a perforation 28 in the top of the base member 2 and through the perforation 29 in the insulating plate 6 and is connected to the screw 22. One end of the wire 27 is connected with a source of current. An insulated wire 30 passes through a perforation 31 in the top of the base member 2 through a perforation 32 in the insulating 105 disc 6 and is connected with the screw 26 and forms the ground portion of the circuit, 110

the other end of the wire 30 being connected with the metal of the machine.

The electric wire 8 has its upper end, as shown in Figure 9, provided with a perforated member 8^a adapted to be received by an insulating cap 34^a. The member 8^a is in engagement with the contact member 34 which is secured to an insulating plate 35. A screw 33 has its head located in a counter-sunk recess in the side wall of a cylindrical crown 44 of a hat 45. The insulating plate 35 is secured to an arcuately shaped plate 36 formed integrally at the upper end of a channel member 7 by means of the screw 33. It will be noted that the sleeve 34^a has a flange engaging the member 8^a and is adapted to insulate the screw 33 from the member 8^a and the plate 34. A nut 33^a is threaded onto the screw 33 and engages the flange of the sleeve 34^a and is adapted to lock the sleeve 34^a, the member 8^a, the contact plate 34, the insulating member 35 and the arcuately shaped plate 36 to the cylindrical crown 44.

The arcuately shaped insulating member 35 is provided with a vertical groove 37 in which is adapted to be seated a grooved portion 38 of the contact member 34. Near the lower end of the groove 38 is formed a notch 39 for a purpose which will be presently described. Both of the constructions are identical on opposite sides of the hat for connecting the wires 8 and 10 to the contact members 34.

A lamp socket 48 adapted to receive the base of a lamp 49 is provided with perforations 50 in its base portion and adapted to receive the shank 51 of the resilient fingers 52 and 53. A set screw 54 is adapted to lock each of the shanks to the socket 48 at diametrically opposite points. The fingers each have a lateral projection 55 which are sprung into the notches 39 in the respective contact members 34 so that the fingers not only provide a means for removably securing the lamp socket 48 in position within the crown 44 of the hat 45 but also form electrical connections between the filament of the lamp 49 and contacts 34 so that the lamp is in circuit with a source of current and the ground.

Perforated lugs 56 are secured to the vertical channel members 7 and 9 and adapted to receive an eye of rods 57. The outer free ends of the rods are flattened, as shown at 58, and are disposed when the vehicle is in position within the ends 59, the metal rods 57 being disposed within the hollow arms 60 of the vehicle. Cotter pins 61 are inserted within the perforations in the lugs 56 and are adapted to hold the rods 57 upon the channel members 7 and 9.

A switch 62 which is operated by the clutch pedal 63 is in the circuit leading from the source of current and connected with the

wire 27 so that when the pedal 63 is operated the lamp 49 is illuminated in order to give a warning to the traffic. A switch 64 mounted in the dash and operated by a push button may be connected with the source of current and with the wire which connects with the wire 27 whereby the lamp 49 may be illuminated when desired and independently of the operation of the clutch pedal 63. The lamp 49 is adapted to be positioned adjacent the neck of the figure so that the face and body portion of the figure will be illuminated. If desired the hat 45 together with the closure 43 which fits over the crown 44 of the hat may be of transparent material instead of metal.

The wire 27 being connected with the source of current and connected with the screw 22 is insulated from the base 2 and the feet 11 and 13 of the standards 7 and 9 so that current will pass through the wire 27 to screw 22, conductor 21 and through the wire 8, contact 34 through finger 52, the filament of the lamp 49, through finger 53, the contact 34 which is connected to the channel bar 9, wire 10 and then grounded on the base member 2. The screws 25 and 26 make electrical connections between the conductor 21 and said base member.

It will be seen by the construction that all the parts are readily removable so that when the lamp burns out the closure 43 may be removed by releasing the screws 41 and the fingers 52 and 53 connected to the socket 48 may be withdrawn upwardly with the lateral projections 55 riding in the grooves 38 in the contacts 34. It is only necessary to insert the bulb and socket within the open portion of the crown of the hat and force the fingers downwardly until the projections 55 again engage the notches 39 in the respective contacts 34.

While I have shown the signal attached to the radiator cap it must be borne in mind that such signal may be attached to any part of the automobile as may be desired without affecting the scope of the invention.

What I claim is:

1. A signal for automobiles adapted for connection to the radiator cap comprising a metal cup-shaped base member, means for connecting the base member to the radiator cap, vertically disposed channel-shaped members secured to the base member, the upper end of each channel-shaped member being provided with an arcuately-shaped plate, an insulating member carrying a contact member and secured to each plate, each contact member being provided with a groove having a notch, a transparent casting in the shape of a figure enclosing the channel-shaped members, a hat, means for securing the plates to the opposite sides of the inner wall of the hat, a lamp socket, laterally opposed resilient fingers carried by

the socket adapted to engage the notches in the grooves of the contact members for locking said socket in position, electric wires passing through the base member and through the channel-shaped members, one of the wires being connected with a contact member, the other wire being connected with the other contact member.

2. A signal for automobiles adapted for connection with the radiator cap comprising a metal base member and attaching screws, means for securing the base member to said cap, channel-shaped standards secured to the base member, contact members secured to the upper end of the standards and insulated therefrom, wires passing through the chan-

nel-shaped members, one wire being connected with a contact member, the other wire being connected with the other contact member, said contact members being provided with grooves, a lamp socket having resilient fingers projecting outwardly from the socket, the free ends of said fingers being adapted to ride in the grooves in the contact members, said contact members being provided with notches formed in the bottom of the grooves adapted to receive the free end of the finger for removably locking the lamp socket to the contact members, a hat for the figure having an open end, and a closure for said open end of the hat

FRANK MICHAEL CRYSTLER.
